SELF PROPELLED VEHICLE FOR TRAINING CUTTING HORSES

Zeke C. Smith, Star Rte., Box 103,
Louise, Tex. 77455

Filed Dec. 11, 1974, Ser. No. 531,539

Term of patent 14 years

Int. Cl. D12—13

U.S. Cl. D12—1

FIG. 1 is a side elevational view of a self propelled vehicle for training cutting horses showing my new design, the side opposite to that shown being identical in appearance to FIG. 1;

FIG. 2 is a front elevational view;

FIG. 3 is a rear elevational view; and

FIG. 4 is a top plan view thereof.

I claim:

The ornamental design for a self propelled vehicle for training cutting horses, as shown.
